UNITED STATES PATENT OFFICE.

ERNEST FUCHS, OF PARIS, FRANCE, ASSIGNOR TO LOUIS RENAULT, OF BELLANCOURT, FRANCE.

ELECTRIC-LIGHTING SYSTEM.

Application filed December 31, 1919. Serial No. 348,708.

To all whom it may concern:

Be it known that I, ERNEST FUCHS, citizen of the French Republic, residing at Paris, Department of the Seine, in France, having P. O. address 111 Boulevard Lxelmans, in the said city, have invented certain new and useful Improvements in Electric-Lighting Systems, of which the following is a specification.

10 The present invention relates to safety devices for electric lighting circuits, more particularly to electric lighting circuits as used in automobiles and other vehicles, where the lamps are fed by a dynamo and 15 a battery of accumulators included in the circuit.

In existing electric lighting systems if from any cause whatsoever the accumulators fail, or if a connection becomes broken, 20 the voltage instantaneously rises in the circuit, and if the speed of the vehicle is sufficient, the lamps are immediately burnt out.

These inconveniences may have very serious effects, at night, for example, when a 25 vehicle is running at full speed.

In order to avoid this danger a great number of systems have been proposed having for their object to maintain a constant voltage, or at least a voltage between given 30 limits in the circuits under consideration. These regulating or controlling systems are generally very complicated and hence the reason for the frequent use of a simple installation, without a regulator or controller, 35 in spite of the inconveniences enumerated above.

The devices forming the subject of the present invention have been designed with the view of efficaciously protecting the lamps 40 without the use of a controller or regulator and without unnecessarily complicating the installation.

In order that the invention may be clearly understood reference is made to the accompanying drawing which shows diagrammatically in Figures 1 to 4 various arrangements in accordance with the present invention. Although the arrangements shown 45 differ slightly from each other, they all embody the same very simple principle which consists in inserting automatically in parallel an auxiliary resistance such that

the voltage cannot appreciably increase at the maximum speed of the motor and thereby burn out the lamps when the accumulators are inoperative or when a connection becomes broken as hereinbefore indicated. 55

In all the figures the same reference letters indicate the same parts.

The generator is indicated at *a*, the battery 60 of accumulators at *b*, and the lamps placed in parallel at *c*, *c*¹, *c*².

The resistance inserted in parallel in the circuit is shown at *l*. The safety device which is there placed in circuit comprises 65 the following members, a solenoid having a soft iron core *d*, a rockable lever *i* having a piece of soft iron *e* at one of its ends, the other end having a catch which in normal running prevents the displacement of a rockable lever *g* which lever is provided with a contact piece *j* at one end, the other end being constantly under the action of a spring *h*, which contact piece makes contact with the terminal *k* connected in the circuit when 70 the lever *i* swings on its pivot under the attraction of the solenoid core *d*. 75

The value of the resistance *l* is such at the greatest speed of the dynamo, the battery *b* being cut out of the circuit, that the 80 voltage cannot rise sufficiently to cause burning out of the lamps.

The action is quite simple. When the tension attains a given value (corresponding to an excess voltage of 15 to 20% for 85 example) the lever *i* is attracted and the contacts *j* and *k* are closed and the resistance *l* is thus inserted in the circuit; at this instant there is a decrease in voltage, unless the dynamo rotates at its maximum 90 speed; this decrease in voltage will generally diminish the intensity of the lighting, but the lamps will not be burned out. Besides the attention of the driver will be directed to the condition of the installation, the decreased lighting effect indicating to him that there is some defect which ought to be remedied when convenient. In any case 95 there will be no necessity to stop the vehicle.

Figure 2 shows a modified arrangement of 100 that hereinbefore described, which consists in substituting for the resistance *l* of Figure 1, a small accumulator of the "alkali" type. Alkaline accumulators can absorb

without the danger of heating, a large number of amperes in a small mass; further, they are not subject to sulphating action. They can therefore ensure the lighting of the vehicle, but by reason of their low output they cannot be employed for starting.

In the two arrangements hereinbefore described, the insertion in the circuit either of the resistance or of the auxiliary accumulator is effected by the action of the lever *i* and the co-acting detent on the lever *g*. Therefore as soon as the lever *i* has been operated to release the lever *g*, it remains in the altered position. It is obvious that the form thereof can be varied without departing from the nature of the invention.

In the arrangement shown in Figure 3, the pawl of the lever *i* is replaced by a trembler switch. In this arrangement the core *d* of the solenoid attracts the lever *l'* at the proper time, which lever is maintained clear of the core by the spring *h*; the insertion in the circuit of the resistance *l* is made when the contacts *j* and *k* are closed. Since there is an abnormal rise in voltage on the line, the core *d* attracts the mass *e*; the contacts *j*, *k* close and the current flows through the resistance *l* and the voltage is lowered immediately; the spring *h* then restores the lever *l'* to its original position and so on.

The oscillation of the lever *l'* thus ensures a practically constant voltage in the line, in spite of deterioration in the condition of the battery *b*.

In order that the driver may be warned that there is something wrong with the installation, a lamp *n* may if desired be placed within range of his vision, the said lamp being connected in parallel with the resistance *l*; when the lamp lights up, it indicates that the safety device is in use, and that there is something wrong with the installation.

In the arrangement shown in Figure 4, the resistance to be inserted in the circuit instead of being separated from the solenoid, is superposed on the winding of the latter in such manner that its action is added to that of the solenoid in order to maintain the mass *e* attracted by the core of the solenoid.

In this arrangement, the action is not that of the trembler of Figure 3. As soon as the voltage in the circuit rises above a certain percentage, the core *d* attracts the mass *e*; the circuit is closed through the resistance *l*, the voltage is lowered, and the electromagnetic force of the solenoid decreases; but, the circuit through the resistance *l* being closed, a new electromagnetic force is added to the former on the core of the solenoid and the mass *e* is maintained against the core as long as the voltage is not reduced below a certain percentage of its normal

value. When this decrease in voltage takes place the spring *h* comes into action and the resistance is cut out of the circuit and the voltage rises and the arrangement operates anew only when the predetermined percentage above the normal is again exceeded.

It is known that in a large number of existing vehicles, the tendency of constructors or designers has been to substitute for the magneto as the source of current for ignition purposes, a battery of accumulators, which can be used for starting and lighting purposes. This results in a simplification of the electrical installation in the vehicle, but on the other hand, any deterioration of the battery results in the suppression of the ignition at the sparking plugs and consequent stoppage of the motor.

With the arrangements hereinbefore described this danger is practically avoided, because there are two batteries of accumulators, either of which can be used if the other be damaged. There is therefore no fear of lack of current for ignition purposes, especially if a battery of the alkaline type be employed, which is not liable to any sulphating action. Under these circumstances, suppression of the magneto becomes possible without fear of being held up or stopped. Various inventors have proposed as auxiliary aids the use of electric cells but these present the inconvenience of deteriorating on open circuit and consequently fail to give sufficient security.

In the arrangement where use is made of an alkaline battery such as *m* for ignition purposes, the ignition circuit is naturally branched to the two terminals of this battery. Besides it is necessary in this arrangement to connect the terminal *r* of the battery corresponding to the contacts *j*, *k*, in Figure 2, with the main circuit through a make and break switch *s*, shown in dotted lines in Figure 2.

In all the arrangements hereinbefore described, the value of the solenoid and resistance are chosen so as to maintain the variations in voltage within normal limits, thereby ensuring safety without the variation becoming too low or rising too high.

Claim:

In an electric lighting system, the combination with a storage battery and a charging dynamo in a common circuit with lamps in parallel connection therewith, a resistance element interposed in said circuit in parallel arrangement with the lamps, a pivoted switch controlling the resistance circuit, means normally tending to move the switch to close the resistance circuit, a detent normally engaging said switch to hold the same open, and a solenoid in the circuit in parallel arrangement with the lamps to be energized by excessive voltage to actuate the detent to release the switch to close the re-

sistance circuit, the values of the resistances of the rheostat and of the resistance element being such that the voltage across the lamp circuit cannot exceed the capacity of the 5 lamps with the storage battery cut out of the circuit and the dynamo driven at its maximum speed.

In testimony whereof I have hereunto set my hand in presence of two subscribing witnesses.

ERNEST FUCHS.
